RAILROAD CAR FILLING DEVICE

Fred M. Atkinson, David F. Mattson, and Albert Leigh Paulson, Minneapolis, Minn., assignors to Atkinson Bulk Transport Company, Minneapolis, Minn., a corporation of Minnesota

Application September 9, 1954, Serial No. 454,882

5 Claims. (Cl. 141—388)

This invention relates to apparatus for efficiently handling pulverulent materials. More particularly it relates to apparatus for filling large containers such as railroad cars and bins to substantially maximum capacity with pulverulent materials while the latter are in a fluidized state.

This invention is related to the invention disclosed and claimed in application for United States Letters Patent entitled Method and Apparatus for Handling Pulverulent Materials, Serial Number 248,955 filed by Fred M. Atkinson on September 29, 1951, Patent Number 2,694,496 and is designed for use in conjunction therewith and/or with modifications thereof utilizing the principles of fluidized conveyance as described and claimed therein. This invention is designed to provide means for most effectively filling railroad cars and the like to maximum capacity when used in combination with the combined fluidizing and conveying mechanism disclosed and claimed in said application.

In the use of the apparatus disclosed in the application referred to above and, in fact, in the transportation of pulverulent material in bulk form by any means, it is important to fill the container such as the railroad car to maximum capacity in order to reduce shipping costs. Thus it is important to find a means for completely filling the railroad car, for example, to the top with a minimum amount of effort. For example, it is important to reduce to a minimum the number of points at which the material is to be introduced since unnecessary handling of the apparatus for introducing the pulverulent materials to the railroad car is thereby avoided. With the equipment previously known for loading railroad cars with pulverulent materials in bulk form, it has heretofore been impossible, as a practical matter, to adequately fill the cars since much unused space would remain within the car after the car had been filled by well accepted methods. The use of the equipment disclosed and claimed in this application in cooperation with the equipment disclosed in the application referred to above reduces this waste of space substantially. It is possible, of course, to mount a material delivery tube at the top of each railroad car and extending throughout the length thereof and having frequent openings along its length in order to effectively fill such a car, but this type of structure requires an unnecessarily large amount of materials and involves substantial cost since one such structure must be provided for each car. Our invention is designed to overcome these disadvantages.

It is a general object of our invention to provide a novel and improved container-filling device for completely filling a container to substantially maximum capacity with pressurized fluidized pulverulent material.

A more specific object is to provide a novel and improved container-filling device for completely filling a container to substantially maximum capacity with pressurized fluidized pulverulent material, the device being very simple and inexpensive in both construction and operation and filling the container to a greater degree

2

than has heretofore been practical with previously known equipment.

Another object is to provide a novel and improved container-filling device, which when used together with apparatus for conveying such pulverulent materials under pressure, will fill a railroad car with such materials to a greater degree than has heretofore been practical with previously known equipment while being applied to only two openings of the car.

10 Another object is to provide a device of the type described hereinabove which will fill a railroad car to 10% to 20% greater capacity than has heretofore been practical with any previously known equipment.

Another object is to provide a device of the type described hereinabove which is sufficiently light in weight that it may be readily moved from hatch to hatch of a railroad car by a single operator.

15 Another object is to provide a container-filling device which is readily removable and controllable by a single man and with a minimum of effort.

20 These and other objects and advantages of our invention will more fully appear from the following description made in connection with the accompanying drawings, wherein like reference characters refer to the same or similar parts throughout the several views, and in which:

25 Fig. 1 is a vertical sectional view of a typical railroad car showing one embodiment of our invention in operation with the car more than one-half filled from a single inlet;

30 Fig. 2 is a plan view on an enlarged scale of the same embodiment as is shown in Fig. 1;

35 Fig. 3 is a vertical sectional view, with parts thereof shown in elevation and parts shown in section, taken along line 3—3 of Fig. 2, the vertical portion of the angle frame members being omitted.

40 One embodiment of our invention as shown in Figs. 1—3 may include a cover member 5 which has a centrally disposed opening 6 formed therethrough. This cover member 5 is sufficiently large in diameter to cover the conventional hatch opening 7 of a conventional railroad car 8. The cover member 5 has a sealing member 9 secured to the underside thereof and extending along the peripheral portions, the sealing member 9 being circular in shape and sufficiently large in diameter to completely surround the hatch opening 7 of the box car when the cover member is placed in closing position relative to the hatch opening 7. As best shown in Fig. 3, the sealing member 9 is preferably formed of foam rubber and engages the hatch defining portions of the railroad car 8 so as to effectively preclude the passage of air outwardly between the cover member 5 and the hatch opening defining portions of the car 8.

45 Mounted on the cover member 5 and extending upwardly through its opening 6 is a rigid spout or conduit member indicated generally as 10. This rigid spout has an upper end portion 11 which is externally threaded as best shown in Fig. 3. The upper end 11 is thereby adapted to be attached to the discharge conduit of a pulverulent material fluidizing and conveying system such as is disclosed in the application, Serial Number 248,955 referred to hereinabove.

50 The rigid spout 10 has a lower end portion 12 extending below the cover member 5 and closely adjacent to the inner surface 8a of the top of the railroad car 8. As best shown in Fig. 3 this lower end portion is curved or bent to extend normally to the upper end portion 11 and parallel to the plane of the cover member 5. It has a discharge opening 13 which is directed substantially parallel to the plane of the cover member 5 and discharges the fluidized pressurized pulverulent material substantially horizontally outwardly therefrom. This spout 10 is swing-

able or rotatable about a substantially vertical axis designated in Fig. 3 by the numeral 14. A pair of handle members 15 and 16 are secured to the upper end portion of the spout 10 and extend outwardly therefrom to facilitate the rotation of the spout 10 about the axis 14. These handle members 15 and 16 are aligned with the discharge portion 12 of the spout 10 as is best shown in Fig. 3.

A circular metal guide ring 17 encircles the upper end portion 11 of the spout 10 in loose fitting relation and is rigidly supported by a plurality of support members such as 18, the lower ends 18a of which are secured to the upper surface of the cover member 5. Set screws 19 extend through this guide ring to secure the spout 10 in any desired position. A circular sealing member 20 in the form of packing encircles the spout 10 at the upper surface of the cover member 5 and is held in snug fitting airtight sealing relation around the spout 10 by a metal ring 21 having an off-set base 21a secured to the cover member by rivets or bolts or any other conventional manner as shown.

Secured to the top of the cover member 5 and arranged to form a generally triangularly shaped framework are three angle frame members 22, 23 and 24. These frame members are made of angle iron and are welded together at their ends and rigidly secured to the top of the cover member. A slot such as 25 is formed at each of the corners of the frame-work to cooperate with clamp members 26 normally provided on the railroad car for securing the hatch cover thereto.

In use in the filling of a railroad car or a bin having a similar inlet, the hatch cover is removed and the cover member 5 is applied to the hatch opening 7 of the railroad car with the sealing member 9 surrounding the same. The clamps 26 are swung into the slots 25 and tightened to secure the cover member to the railroad car 8, the sealing member 9 thereupon preventing the escape of air in any appreciable quantities. The discharge conduit of an apparatus such as is disclosed and claimed in the application, Serial Number 248,955, is then threaded onto the upper end portion 11 of the spout 10 so that when the conveying apparatus disclosed and claimed in said application is operated, the fluidized pressurized pulverulent material will flow out of the spout 10 in a substantially solid stream, the pulverulent material flowing much like the water which flows from a fire hose without a nozzle when connected to a fire hydrant. The fluidized pulverulent material will flow to all corners of the railroad car and as it reaches a level approaching the top of the car 8, it will be forced into all corners and to the far sides of the car. The operator will first direct the discharge end portion 13 toward the adjacent end of the car until that end has been substantially completely filled to the top and he may then swing it toward the more remote end or toward either side of the car to insure that the material fills the car completely at its outermost portions.

We have found that through the use of the device disclosed and claimed herein it is possible to fill such a railroad car to a 5% to 20% greater capacity than has been possible as a practical matter with other equipment heretofore known. We have found that a railroad car can be completely filled by merely applying this device to two separate hatches, one adjacent each end of the railroad car, and that through such application substantially all of the space within the car is utilized. Thus a far greater payload is made possible through the use of this device.

This device is particularly effective when used with conveying apparatus of the type claimed in the application for patent, Serial Number 248,955, referred to hereinabove wherein pressures of 5 to 30 pounds are utilized with concentrations of 50 to 80 pounds of flour per pound of air travelling at velocities of 300 to 1500 feet per minute at the point of entrance into the discharge conduit of the conveying system.

It will be noted that our railroad car filling device is relatively simple and inexpensive in construction and operation as compared to other equipment for effectively filling such means of conveyance. It will be noted that it can be operated very easily by only one man since it is light in weight and can be directed with a minimum of effort. It should also be noted that a single loading device such as is disclosed and claimed herein will suffice for all railroad cars so that the structure need not be duplicated for each railroad car since it can be moved from hatch to hatch. In addition, it needs to be applied to the car at only two points and thus minimizes the attention and effort required in the operation of such equipment.

Thus it can be seen that we have provided an extremely simple and relatively inexpensive device which will effect substantial savings in shipping costs and in the capital outlay required for such car loading operations.

It will, of course, be understood that various changes may be made in the form, details, arrangement and proportions of the various parts without departing from the scope of our invention.

What is claimed is:

1. A bulk-container-filling device for filling a container having a material inlet to substantially maximum capacity with pressurized fluidized pulverulent material, said device comprising a seal member adapted to fit over and seal the material inlet of such a container, said seal member having a centrally disposed opening formed therethrough, and a rigid spout mounted on said seal member and extending through said opening, said spout having an upper end adapted to be connected to a source of fluidized pulverulent material under relatively high pressures, and constituting a material inlet, said spout having a lower end portion extending substantially parallel to the plane of said seal member and constituting a discharge outlet for such fluidized pulverulent material, said spout being swingable about an axis extending substantially normal to said lower end portion and said seal member to effect discharge of such fluidized pulverulent material in all directions as desired and thereby fill the container to substantially maximum capacity.

2. A bulk railroad-car filling device for completely filling a railroad car having inlets at the top thereof to substantially maximum capacity with bulk pressurized fluidized pulverulent material, said device comprising a sealing cover member adapted to fit over one of the inlets of such a railroad car in snug-fitting relation to effectively seal the same, said cover member having an opening formed therethrough, and a rigid spout extending through said opening and having an open upper end portion constituting a fluidized material inlet and having a lower end portion constituting a discharge outlet for such material, said upper end portion being adapted to be connected to a source of fluidized pulverulent material under relatively high pressures, said lower end portion extending substantially normal to said upper end portion and discharging such fluidized pulverulent material substantially horizontally within the car when said upper end is so connected, said spout being rotatable about an upright axis within the opening of said cover member to effect discharge of such fluidized pulverulent material in all directions within the car and thereby fill the car to substantially maximum capacity.

3. A bulk-container-filling device for completely filling a container having a material inlet to substantially maximum capacity with pressurized fluidized pulverulent material, said device comprising a flat cover member adapted to fit over and close the material inlet of such a container, sealing means extending along the peripheral portions of said cover and secured to the underside thereof and extending downwardly therefrom to effectively seal off the material inlet when said cover member is applied thereto, said cover member having a centrally disposed opening formed therethrough, and

a rigid spout mounted on said cover member and extending upwardly through said opening, said spout having an upper end adapted to be connected to a source of fluidized pulverulent material under relatively high pressures and constituting a material inlet, said spout having a lower end portion extending substantially parallel to the plane of said cover member and constituting a discharge outlet for such pulverulent material, said spout being rotatable about an axis extending substantially normal to said lower end portion and said cover member to effect the discharge of such fluidized pulverulent material in all directions within the car as desired and thereby fill the container to substantially maximum capacity.

4. A bulk-container-filling device for filling a container having a material inlet to substantially maximum capacity with pressurized fluidized pulverulent material, said device comprising a cover member adapted to fit over and effectively close the material inlet of such a container, said cover member having a centrally disposed opening formed therethrough, a rigid spout mounted on said cover member and extending upwardly through said opening in substantially air-tight-fitting relation, said spout having a vertically extending upper end portion adapted to be connected to a source of fluidized pulverulent material under relatively high pressures and constituting a material inlet, said spout having a lower end portion extending parallel to the plane of said cover member and constituting a discharge outlet for such fluidized pulverulent material, said spout being swingable about an axis normal to the plane of said cover member to effect discharge of such pulverulent material in all directions within the car as desired and thereby fill the container to substantially maximum capacity, guide means vertically spaced from said cover member and supported thereby and guiding said spout during its swinging movement, and means connected to the upper end portion of said spout and extending outwardly therefrom for facilitating the swinging of said spout about said axis.

5. A bulk-container-filling device for filling a container having a material inlet to substantially maximum capacity with pressurized fluidized pulverulent material, said device comprising a cover member adapted to fit over and close the material inlet of such a container, said cover member having a centrally disposed opening formed therethrough, a rigid spout mounted on said cover member and extending upwardly through said opening, said spout having an upper end adapted to be connected to a source of fluidized pulverulent material under relatively high pressures and constituting a material inlet, said spout having a lower end portion extending substantially parallel to the plane of said cover member and having a discharge outlet directed substantially parallel to said cover member and positioned closely adjacent thereto, said spout being swingable about an axis extending substantially normal to said cover member to effect discharge of such fluidized pulverulent material in all directions within the car as desired to thereby fill the container to substantially maximum capacity, sealing means connected to said cover member and surrounding said spout to effectively prevent the escape of air between said spout and said cover member, means for manually turning said spout about said axis, and circular guide means vertically spaced from said cover member and supported thereby, said guide means encircling the upper end portion of said spout and guiding the same during the swinging movement of said spout relative to said cover member.
